CLAIM

The ornamental design for a wrist rest, as shown and described.

DESCRIPTION

FIG. 1 is a top right front perspective view of a wrist rest showing our new design;
FIG. 2 is a top plan view thereof;
FIG. 3 is a bottom plan view thereof;
FIG. 4 is a rear elevational view thereof;
FIG. 5 is a left side elevational view thereof; the right side elevational view being a mirror image; and,
FIG. 6 is a front elevational view thereof.

FIG. 1

FIG. 2

FIG. 3

FIG. 4

FIG. 5

FIG. 6
